UNITED STATES PATENT OFFICE.

MAGDELIN CHRISTIAN GLEERUP-MÖLLER, OF COPENHAGEN, DENMARK.

PUNCH FOR PERFORATING BELTS.

1,338,296.

Specification of Letters Patent. Patented Apr. 27, 1920.

Application filed July 9, 1919. Serial No. 309,720.

To all whom it may concern:

Be it known that I, MAGDELIN CHRISTIAN GLEERUP-MÖLLER, manufacturer of engines, citizen of the Kingdom of Denmark, residing at No. 103 Jagtvej, Copenhagen, Denmark, have invented certain new and useful Improvements in Punches for Perforating Belts and the like, of which the following is a specification.

10 Joints in driving belts and the like are made by using belt fasteners provided with several hooks engaging a series of holes in each of the belt ends to be joined, and it is, therefore, of importance that the said holes 15 in the belt ends be spaced in a manner corresponding exactly to the distance between the hooks on the belt fastener, by means of which the belt ends are to be joined. It is also of importance to have the holes located 20 exactly at the proper distance from the edge of the belt end.

The present invention relates to a punch whereby the holes in the belt end may be spaced in such a manner that there will be 25 exactly the pre-determined distance between them, and such holes will also be spaced the proper distance from the edge of the belt end.

The present invention is mainly characterized by a carriage guided so that it may 30 slide transversely of the punch, means being provided for clamping the belt end to the said carriage which is provided with a number of bores or holes spaced uniformly and 35 serving to receive, when the punch is closed, a plug or the like provided on the jaw opposite the carriage, so that the hollow-punch cannot pierce the belt end unless the carriage occupies such a position that one of 40 the holes in the carriage is directly below the said plug. The invention is further characterized in that the carriage movable transversely of the punch is guided and shaped in such a manner that the punch 45 proper may be turned through an angle of about 90° relatively to the carriage which later, in its new position, may again be moved across the punch, so that the belt end may be perforated during the first motion 50 and, during the second motion, the edge of the belt end may be trimmed by means of a knife provided on the one jaw of the punch which supports the carriage, the said

knife being brought into its working position by the rotation of the punch. 55

The invention is illustratively exemplified in the accompanying drawings, in which:

Figure 1 shows, in side-elevation, the punch and the transversely movable carriage and, in dotted lines, the altered position of the punch relatively to the carriage. 60

Fig. 2 shows, in top-view, the carriage movable transversely of the punch.

Figs. 3 and 4 show the bottom carriage in vertical section and in top-view, respectively. 65

In the drawing, 1 indicates the punch proper, one jaw 2 thereof supporting a suitable guiding member 3 firmly connected to the jaw, and located in the notch 4 in the bottom carriage 5, (Fig. 4), while the bottom carriage 5 is hinged to the jaw 2 by means of the pin 6. The top carriage 7 is guided by the horizontally projecting edges of the bottom carriage, and the carriage 7 70 may be moved in a direction across the punch. In Fig. 2, the top carriage 7 is shown as provided with a series of holes 8 disposed at exactly equal distance from each other, the said distance corresponding exactly to the distance between the hooks on the belt fastener to be used in joining the belt. 75 Besides the perforated raised plate 9 with the holes 8, the carriage supports also an eccentrically disposed roller or the like 80 10 adapted to be turned by means of a handle 11 or the like, the said roller serving to clamp the belt end in the carriage 7, after the belt end has been placed in position therein, i. e. after it has been pushed a sufficient 85 distance over the top carriage, and its longitudinal edge guided by being pressed against the guiding strip 12. 90

After the belt end has been clamped in the top carriage 7 the punching operation 95 commences, the punch being operated once for every hole to be produced. The holes in the belt end are punched by the hollow-punch 13 provided on the jaw 14, the latter also carrying a plug or guiding pin 15 of 100 somewhat smaller diameter than the holes 8 in the plate 9 on the carriage. The plug 15 cannot move downward unless it is directly over one of the holes 8, and, consequently, the punch cannot be operated unless the carriage is in such a position that 105

the plug 15 may move down into one of the holes 8. At the place where the hollow-punch 13 is pressed down toward the carriage 7, a copper bar or the like 16 is soldered to the carriage. By moving the carriage in a direction across the punch step-wise, and each time a distance corresponding to the distance between two adjacent holes 8, the result will be that the belt end 10 will be perforated with holes located at exactly equal distances from each other.

When the punching operation is finished, the belt end may be trimmed by means of the same punch, so that the trimmed edge 15 will be located exactly at the proper distance from the perforations. This is effected by the carriage being moved into such a position that the bottom carriage 5 and the guiding piece 3 will come centrally 20 below a corresponding opening 17 in the top carriage 7, Fig. 2. When the parts are in this position, the punch may be moved about the pivot 6 into the position shown in dotted lines in Fig. 1. During the rotation, 25 the carriages 5 and 7 retain their position relatively to one another, while the jaw 2 and the guiding piece 3 revolve about the pin 6. The rotation is continued, until the knife 18 disposed at right angles to the jaw 2, and supported by the same, comes directly opposite the longitudinal slot 19 below the plate 9 in the carriage 7, Fig. 2. At the same time, one edge 20 on the guiding piece 3, Fig. 1, will be so located that 35 it may enter the guiding slot in the top carriage together with the notched guiding edge on the bottom carriage. After the parts have been brought into the said positions relatively to each other, the cutting 40 is performed by moving the punch length-wise of the carriage.

I claim:

1. In a punch, the combination with a pair of relatively movable jaws, of an article supporting member movable on one of said jaws, and means for predetermining the spacing of holes punched in said article by the punch.

2. In a punch, the combination with a pair of relatively movable jaws, a perforating tool and a projection carried by one of said jaws, of an article supporting member

movable on the other jaw, said member having perforations into which the projection is adapted to successively enter. 55

3. In a punch, the combination with a pair of relatively movable jaws, a perforating tool and a projection carried by one of said jaws, of a carriage slidably mounted on the other jaw, and a plate on said carriage 60 having spaced perforations into which said projection may be depressed by relative movement of said jaws.

4. In a punch, the combination with a pair of relatively movable jaws, of an article supporting member movable on one of said jaws, means for clamping an article 65 in position on said member, and means for predetermining the spacing of holes punched in said article by the punch. 70

5. In a punch, the combination with a pair of relatively movable jaws, of a carriage slidably mounted on one of said jaws and movable transversely thereof, a perforated plate on said carriage, a pin on the 75 other jaw adapted to enter the perforations in said plate, and punching members carried by said jaws and operative only when said pin enters one of said perforations.

6. The combination with a punching tool, 80 of a carriage pivotally connected thereto and movable transversely thereof, and a cutter blade carried by the tool and adapted to cut articles supported by the carriage.

7. The combination with a punching tool, 85 of a longitudinally slotted carriage pivotally connected thereto and movable transversely thereof, and a cutter blade carried by said tool and adapted to project into the slot in the carriage and cut an article supported by said carriage during relative movement between the tool and carriage. 90

8. The combination with a punching tool, 95 of a carriage pivotally connected thereto, and movable transversely thereof, a cutter blade carried by the tool and adapted to cut articles supported by the carriage during relative movement between the tool and carriage, and means for guiding the blade during the cutting operation. 100

In testimony whereof he affixes his signature.

— MAGDELIN CHRISTIAN GLEERUP-MÖLLER.
